(57) **CLAIM**

I claim the ornamental design for a fire pit, as shown and described.

DESCRIPTION

FIG. 1 is a top perspective view for a fire pit in an open configuration showing my new design.

FIG. 2 is a front view in an open configuration.

FIG. 3 is a rear view in an open configuration.

FIG. 4 is a top plan view in an open configuration.

FIG. 5 is a bottom plan view in an open configuration.

FIG. 6 is a first side view in an open configuration.

FIG. 7 is a second side view in an open configuration; and, FIG. 8 is a top perspective view of the fire pit in a closed configuration.

The broken lines shown in the drawings illustrate portions of the fire pit that form no part of the claimed design.
